UNITED STATES PATENT OFFICE.

JOHN EBBERT, OF ROCKAWAY BEACH, NEW YORK, ASSIGNOR TO PHILLIP A. HALL, OF CHICAGO, ILLINOIS.

SPIKE-EXTRACTOR.

SPECIFICATION forming part of Letters Patent No. 293,431, dated February 12, 1884.

Application filed December 8, 1883. (No model.)

To all whom it may concern:

Be it known that I, JOHN EBBERT, of Rockaway Beach, in the county of Queens and State of New York, have invented a new and Improved Spike-Extractor, of which the following is a full, clear, and exact description.

This invention relates to certain improvements in my new and improved spike-extractor shown and described in Letters Patent No. 290,011, which were granted to me December 11, 1883; and the invention consists of the combinations and arrangements of parts substantially as hereinafter described and claimed.

Reference is to be had to the accompanying drawings, forming a part of this specification, in which similar letters of reference indicate corresponding parts in all the figures.

Figure 1 is a side elevation of my improved spike-extractor applied for drawing a railway-spike, showing in full lines the positions the parts assume in starting the spike, and in dotted lines the positions they assume when the spike has been fully drawn. Fig. 2 is a sectional front elevation of the claw and cam-ring removed from the other parts of the device. Fig. 3 is a front elevation of a modified form of claw, and Fig. 4 is a bottom view of the cam-ring.

The sectors *a* *b* are toothed, and linked together by the plates *e*, and secured upon the support *k* *l* in the same manner as shown and described in my above-mentioned patent. The sector *a*, instead of being formed with a lever or handle, as in my said patent, is formed with the socket *a'*, for receiving the separate lever *g*, for rocking the sector *b*, for drawing the spike.

h is the bolt to which the claws *h'* *h*' are attached. This bolt *h* is screw-threaded at its lower end, and is hinged at its upper end to the angle of the sector *a* by the pin *f*. The claws *h'* *h*' are attached to the bolt *h* by the internally-screw-threaded sleeve *j*, with the head *j'* of which the claws are formed, or to which head they are rigidly secured or pivoted. When the claws *h'* are pivoted to the head *j'* of the sleeve *j*, they are by preference each formed with the upwardly and outwardly

projecting stems *h*², as shown in Fig. 2. With

this form of claw I shall employ the cam-ring *k*, formed with the eccentric or cam grooves *k'* *k*², and placed upon and adapted to be turned upon the sleeve *j* and upper ends of the stems *h*², for opening and closing the claws, 55 and for locking the claws in closed position upon the spike or other object to be drawn; and, by preference, the said cam-ring *k* is formed with the lugs *k*² *k*², by which the ring may easily be turned with the hand for opening or closing the claws, and the ring is held in place upon the sleeve *j* by means of the plate or nut *k*³, screwed upon the screw-threaded portion of the connecting-bolt *h*, as shown clearly in Fig. 2. The claws *h'* are so arranged with the stems *h*² and cam-ring *k* that by turning the ring to the left the upper ends of the stems *h*² will be drawn toward each other, thus opening the claws, so that they may be passed directly down over the head of the 70 spike, if found necessary; and by turning the said cam-ring to the right the stems *h*² will, forced away from each other, cause the claws to grasp and firmly hold the spike or whatever may be placed between them; and by 75 employing the sleeve *j* and bolt *h* the claws may be easily adjusted by turning the sleeve up or down upon the bolt *h*, for adapting the extractor to its work—as, for example, to railroad-rails of different heights; and by forming 80 the sector *a* with the socket *a'* the extractor is adapted to be used with a separate handle, which may be removed and replaced at pleasure, making the tool more convenient than when made with a rigid handle. Besides, the 85 socket *a'* renders the tool stronger and more durable and cheaper to make than when made with a rigid handle.

Having thus fully described my invention, I claim as new and desire to secure by Letters 90 Patent—

1. In a spike-extractor, the combination, with the screw and the pivoted claws having upwardly-projecting stems or arms, and an internally-screw-threaded sleeve, of the cam-ring fitted upon said sleeve, and the claw stems or arms, and the nut holding the cam-ring on the sleeve, substantially as and for the purpose set forth.

2. In a spike-extractor, the combination,

with the screw and the pivoted claws having upwardly-projecting stems or arms, and the internally-screw-threaded sleeve, of the cam-ring having opposite eccentric grooves on its 5 under side, which engage the upper ends of the claw stems or arms, substantially as and for the purpose set forth.

3. In a spike-extractor, the combination, with the screw and the pivoted claws having 10 upwardly-projecting arms or stems, and the internally-screw-threaded sleeve, of the cam-ring having opposite eccentric grooves, and the nut which holds the cam-ring upon the sleeve, substantially as and for the purpose 15 set forth.

4. The combination, with the connecting-bolt *h*, sleeve *j*, and pivoted claws *h' h'*, formed

with stems *h² h²*, of the cam-ring *h*, placed upon the sleeve and upper ends of the stems and adapted to be turned, substantially as and for 20 the purposes set forth.

5. In a spike-extractor, the bolt connected to the claws, the latter having a cam-ring, the clamping action thereof securing the claws upon the spike or other object, in combination 25 with the intergearing sectors linked together, and one being pivoted to the upper end of the said bolt, and having a socket and handle, substantially as and for the purpose set forth.

JOHN EBBERT.
